UNITED STATES PATENT OFFICE.

EDWIN A. FARGO, OF ATTLEBORO, MASSACHUSETTS.

CUFF BUTTON.

Application filed August 24, 1923. Serial No. 659,112.

To all whom it may concern:

Be it known that I, EDWIN A. FARGO, a citizen of the United States, residing at Attleboro, in the county of Bristol and State 5 of Massachusetts, have invented certain new and useful Improvements in Cuff Buttons, of which the following is a specification.

This invention relates to separable cuff buttons of the class which are composed of 10 two separate members each having an outer and an inner head, the latter heads of each member being adapted to be passed through the buttonholes of a cuff to hold its member therein, said button members being provided 15 with means whereby they may be connected and disconnected at will.

With these and other objects in view, the invention consists of certain novel features of construction as will be more fully described, and particularly pointed out in the appended claims.

In the accompanying drawings:

Fig. 1 is a side elevation of my improved button showing the button members connected together.

Fig. 2 shows the button members as separated.

Fig. 3 is a top view of the inner head of one of the members, showing the pair of 30 cooperating stud gripping plates mounted therein.

Fig. 4 shows these plates as moved inwardly and laterally to enlarge the opening and release the stud of the opposite button 35 member.

Fig. 5 is an elevation showing fragmental portions of the button members, the head carrying the gripping plates being shown in section on line 5—5 of Figure 3.

Fig. 6 is a view similar to that shown in Fig. 5 and sectioned on line 6—6 of Figure 3.

Figure 7 is an enlarged view on line 7—7 of Figure 3, illustrating the socket or opening in which the end of the operating spring is mounted.

Figure 8 is a section showing a modified construction in which the grip plates do not abut against each other but each against a 50 separate guide member.

It is found in the practical construction of separable cuff link buttons, of advantage to lock the button members together so that they will not separate under excessive 55 strains, the same being locked firmly together in such a way as to require an opera-

tion of the locking members in order to release the button parts to separate: and the following is a detailed description of one means by which this result may be obtained:—

With reference to the drawings, 10 and 11 designate the outer heads of the opposite button members and 12 and 13 the inner heads of these members. The head 12 is 65 preferably provided with a stud 14 having a substantially squared shoulder 15 under its head, while the inner head 13 of the other button member is preferably formed hollow, as best illustrated in Figures 3 and 4. 70 In this hollow head, I have mounted a pair of oppositely slidable locking plates 16. The ends of these plates are arranged to abut against each other and these ends are formed at an angle to each other as at 17, 75 and notched at 18 to form between them a stud-receiving opening. The outer end of each of these plates is provided with an operating presser member 19 which when pressed inwardly causes these angularly 80 faced ends to ride one upon the other and move these plates laterally in opposite directions into the position illustrated in Figure 4, thereby enlarging the central opening in a lateral direction to release the stud 85 and permit the button members to be separated. These plates are normally pressed to closed position by means of springs 20, one end of each of which is secured in the edge of its adjacent plate by slotting the 90 plates and inserting the end of the spring therein and then closing over the stock of the plate as at 21, see Figure 7, onto the spring end to firmly grasp and retain it in the edge of its plate.

In operating my improved button members, it is only necessary to press the two members together which causes the tapered head of the stud to force the plates 16 apart against the pressure of their springs, which plates after the stud has entered at once returns to grip and firmly retain the stud between them, requiring a pressure of the thumb and finger on the presser members 19 to move the plates to release the 100 stud and permit the button members to be separated.

By this construction, the button members are firmly locked together and will not separate under any undue strain until the presser lugs have been forced inwardly to release the connecting stud.

I have shown and described the ends of the grip plates 16 as having abutting, inclined, end surfaces, but as shown in Figure 8 the inclined surface of the plates may 5 abut against a pin or other bearing member 22, whereby the operation of one plate alone will not suffice to release the stud 14.

The foregoing description is directed solely towards the construction illustrated, but 10 I desire it to be understood that I reserve the privilege of resorting to all the mechanical changes to which the device is susceptible, the invention being defined and limited only by the terms of the appended claims.

15 I claim:

1. A separable cuff link button formed of two independent button members each having an outer and an inner head, the latter head being adapted to pass through 20 the buttonholes of a cuff and retain the members therein, a stud on the inner head of one of said members, and a snap grip comprising a pair of cooperating slide members mounted in the other of said inner 25 heads and operable by hand pressure to receive combined and opposite longitudinal and lateral movements to release said stud.

2. A separable cuff link button formed of two independent button members each having an outer and an inner head connected by a post, the latter head being adapted to be passed through the buttonholes of a cuff and retain the link member therein, a short stud having a reduced neck portion 30 adjacent the outer face of the inner head of one of said members, a pair of cooperating spring pressed slide plates having inclined abutting ends, said plates being located in the corresponding inner head of the 35 other member adapted to receive and securely lock said stud between them, and ex-

tending presser members by which said plates may be moved both laterally and longitudinally in the same plane to release said stud and permit the separation of said button members. 45

3. A separable cuff link button formed of two independent button members, each having an outer and an inner head, the latter head being adapted to pass through the buttonholes of a cuff and retain the button members therein, a stud on the inner head of one of said members, a pair of cooperating spring-pressed lock plates in the corresponding head of the other member having inclined guiding surfaces and a cooperating stud-engaging edge, and a presser finger on one of said plates by which it may be moved inwardly towards the opposite plate to slide along the inclined surfaces 60 causing the plates to be moved laterally from each other to release the stud gripped between them. 55

4. A separable cuff link button formed of two independent button members, each having an outer and an inner head, the latter head being adapted to pass through the buttonholes of a cuff and retain the button members therein, a stud on the inner head of one of said members, a pair of cooperating spring pressed lock plates in the corresponding head of the other member having abutting ends formed on an angle to their common axis and having cooperating notches in their ends forming a stud receiving opening, and an extending presser finger on each of said plates by which said plates may be moved toward each other and also laterally to enlarge said opening and release the stud held therein. 75

In testimony whereof I affix my signature.
EDWIN A. FARGO.
